UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed May 3, 1922. Serial No. 558,185.

To all whom it may concern:

Be it known that I, EDWIN E. BARNEY, citizen of the United States, and resident of New Rochelle, in the county of Westchester and State of New York, have invented certain new and useful Improvements in Typewriting Machines, of which the following is a specification.

My present invention relates to back spacing mechanism for typewriting machines, and its principal object is to provide new and improved mechanism of the character specified.

To the above and other ends which will hereinafter appear my invention consists in the features of construction, combinations of devices and arrangements of parts hereinafter described and particularly pointed out in the claims.

20 In carrying out my invention in the present instance I have applied it to a typewriting machine of the character disclosed in the application of John H. Barr and Edwin E. Barney, Sr. No. 403,780, filed

25 August 16, 1920, and in the application of A. W. Smith, Sr. No. 476,788, filed June 11, 1921, but it is to be understood that various features of the invention may be adapted to other styles of machines.

30 In the accompanying drawings:

Figure 1 is a fragmentary front-to-rear vertical sectional view of said typewriting machine, only so much of the machine being shown as is necessary to a complete understanding of the invention.

35 Figure 2 is a transverse vertical sectional view taken on planes indicated by the section line 1—1 in Fig. 1 and looking rearward in the direction of the arrows at said line.

40 Figure 3 is a fragmentary horizontal sectional view taken on planes indicated by the section line 2—2 in Fig. 2 and looking downward in the direction of the arrows at said line.

45 Figure 4 is a fragmentary view showing parts of the back spacing mechanism from the view-point of Fig. 2, but illustrating said parts in their operated positions.

50 Figure 5 is a fragmentary front elevation showing the back spacing latch and the member for actuating it as associated in a 92-character, single shift, typewriting machine.

55 As appears from the drawings, the main

frame of the machine comprises side plates 1 connected at the front and rear by cross plates 2 and 3. A carriage arranged above the main frame comprises an inclined transverse bar 4 provided with forwardly extending end bars 5. The bar 4 is grooved to provide seats for anti-friction rollers 6, the upper set whereof co-operates with a grooved seat formed in a stationary guide bar 7 mounted on an angular bed plate 8 which is suitably fixed to the side plates 1. The forward portion of the bed plate terminates in an extension 9 formed with a grooved seat for the lower set of rollers 6. Journaled on the traveling carriage 4, 5, 70 is a roller platen 10 with whose front face co-operate type bars 11, the set of type bars being arranged in an arc below the platen, their free ends normally resting on a pad 12 mounted on a curved support 13. The type bars are pivoted on a wire 14 mounted on a vertical type bar support or segment 15, each type bar being provided forward of its pivot with a contact face 16 for co-operation with the escapement devices. Below its pivot each type bar is formed with a cam slot 17 which is engaged by a headed pin 18 projecting laterally from the lower arm of a bell crank 19. The set of bell cranks 19 are arranged in guide slots 20 formed in the support 13 and have a common pivot wire 21 which is mounted on said support. Each bell crank 19 is connected at its shorter arm by a link 22 with an angular lever 23 pivoted on a wire 24 80 in a sub-frame 25 detachably secured to the main frame, the set of levers 23 being received in parallel guide slots 25^a formed in the sub-frame. Each lever 23 has secured to it a headed pin 26 which co-operates with a slot 27 in a key lever 28, the set of key levers being pivoted on fulcrum wires 29 secured to the sub-frame 25. When one of the printing key levers is depressed it will, through the described train of connections, operate the associate type bar 11, said type bar being swung upwardly and rearwardly into co-operative contact with the platen and the paper thereon. During printing movements, the type bars will 100 actuate the escapement devices causing them to co-operate to permit the leftward step-by-step movement of the carriage under the pull of a carriage motor comprising a spring driven drum 30 mounted on the frame of 110

the machine and connected to the carriage by a band or strap 31 secured at one end to a projection 32 on the drum 30 and provided at its opposite end with a stirrup 33 which hooks over a pin 34 on the carriage bar 4. The escapement devices comprise a curved universal bar 35 which is actuated by the contact faces 16 of the type bars and is comprised in a universal bar frame which 10 is mounted on the segment 15 and includes a rearwardly extending arm 36 that is adapted to actuate a dog carrier or rocker 37 mounted to swing on stationary pivots 38 and 39 that project from hanger arms 15 40 depending from the bed plate 8. Mounted on the rocker 37 are escapement dogs 41 and 42 which co-operate with a toothed escapement wheel 43 fixed to a shaft 44 adapted to rotate in bearings on the bed 20 plate 8. A spring pressed pawl 45 is pivoted to the front face of the escapement wheel at 45^a and the tooth of said pawl is maintained by its spring 45^b constantly engaged with a toothed member or feed pinion 25 46 loosely mounted on the shaft 44, said pinion inter-meshing with a feed rack 47 fixed to the lower side of the carriage by screws 48. The construction is such that leftward movements of the carriage will be 30 transmitted through the feed rack 47 and pinion 46 to the pawl 45 and thence to the escapement wheel 43, while during return movements of the carriage the pawl 45 will bob idly in and out of the teeth of the feed 35 pinion 46 as it turns leaving the escapement wheel unaffected. It will be observed that the feed rack 47 is fixed rigidly to the carriage by the screws 48 and that the connection between the feed rack and the feed 40 pinion 46 is a constant or permanent one and never is broken, the disconnection of the escapement mechanism from the carriage during return movements of the latter taking place between the pinion 46 and the 45 escapement wheel 43 through the pawl 45.

My novel back spacing mechanism comprises a slidable member or latch carrying back spacing pawls cooperative with the pinion 46 and actuated by a train of connections terminating in a key in the keyboard. The back-spacing latch or pawl carrier, designated as a whole by the numeral 49, is preferably made of sheet metal in the form of a bar or plate and is 50 provided at its left end with two devices, teeth or pawls 50 and 51 which are formed by lips or edges bent forward at right-angles from the face of the body portion. The pawl 50 is inclined upward at an angle 55 of about 45 degrees to the horizontal and is adapted to act as an actuating pawl, while the pawl 51 which is horizontally disposed functions as an arresting and locking device. At its right-hand end the latch or 60 slide 49 is formed with a recess or seat in-

dicated at 52 thereby providing two contact faces 53 and 54. The latch is provided with two slots indicated at 55 and 56. The right-hand slot 56 is horizontal while the left-hand slot 55 is angular, its extreme 70 right-hand portion being horizontal and slightly above the slot 56 while the left-hand portion of said slot 55 is cut out or lowered, its upper edge being inclined downward and leftward from its junction with the horizontal portion, while its lower edge is cut out until it is substantially horizontal. The slots receive headed shoulder screws 57 which are threaded into stationary parts, the left-hand screw 57 being screwed into the right-hand hanger arm 40 at its front side, the right-hand screw 57 being received in a lug 58 depending from the under side of the bed plate 8. The screws serve to support and guide the latch 49 which is loosely confined between the heads of the screws 57 and the supports 40 and 58 in a vertical position while being adapted to slide leftward and rightward on the shouldered portions of said screws. Furthermore, by reason of the shape of the slot 55 the slide is capable of limited rotary movement at its left side. Normally the latch or slide 49 is maintained in the Fig. 2 position, where the pawls are clear of or separated from the pinion 46, by means of a coiled spring 59 having one end hooked over a pin 60 on the latch, the other end being anchored to a pin 61 projecting forward from the upper part of the lug 58, the pull of the spring being in an inclined direction upward from left to right. The spring tends to maintain the slide at the limit of its rightward movement which is determined by contact of the left-hand end of the slot 55 with the shoulder of its screw 57. Also, the spring 59 tends constantly to swing upward the left end portion of the slide 49 and to lift the pawls.

The actuating devices for the latch 49 110 comprise a bell crank 62 having an upstanding arm 63 and a horizontally disposed arm 64. The bell crank is pivotally supported on a shoulder screw 65 which is threaded into a boss or thickened portion 66 at the inner end of an angular bracket 67 secured by screws 68 to the right-hand frame plate 1, and projecting inward and slightly downward therefrom. The left-hand edge of the upstanding arm 63 of the bell crank is rounded to facilitate co-operation with the latch 49 through either of the contact faces 53 and 54. The machine illustrated in Figs. 1 to 4 is an 84-character machine and in this instance the bell crank co-operates with the left-hand contact face 53, the arm 63 being received in the recess 52 as shown. The horizontal arm 64 of the bell crank is provided with a hole indicated at 69 through which is hooked the upper end of a link 70,

the lower end of said link being pivotally connected at 71 with the rear end of a back spacing key lever 72. Said lever is received in one of the guide slots 25^a and is pivoted on the fulcrum wire 24 near the right-hand side of the machine, the lever extending forward and terminating in a key stem 73 which is provided with a key cap or button 74 located in the upper bank of keys in the keyboard and at the right-hand side. The train of key actuated devices comprising the key lever 72, link 70 and bell crank 62 is maintained in normal position, and restored thereto after actuation, by spring means comprising a coiled spring 75 hooked at one end through a hole in the bell crank arm 63 and anchored at the opposite end to a pin 76 projecting upward from the bracket 67. The spring 75 urges the bell crank 62 rightward on its pivot, tending to press down the link 70 and maintain the forward arm of the lever 72 in contact with the usual stop pad 77.

In operation, when it is desired to back space the carriage for any purpose the key 74 is firmly depressed, swinging the lever 72 on its fulcrum and raising the link 70 which in turn actuates the bell crank 62, causing the curved edge of the arm 63 to press leftward against the contact face 53 of the latch 49 and overcoming the spring 59. As the latch is slid leftward it will be maintained substantially horizontal by reason of the pull of the spring 59 which will hold the bottom edge of the slot 55 at its left-hand side up against the shoulder of the screw 57. Consequently the tooth or pawl 50 will enter the opposite tooth space in the pinion 46 and will engage with and press against the tooth face bounding the left side of said space.

This will cause the pinion 46 to turn, the said engaged tooth of the pinion being thus rotated downward and towards the left, the pushing pawl 50 being carried downward and leftward with said pinion tooth. This movement of the pawl 50 is possible by reason of the shape of the slot 55 which permits a slight downward swing or rotary movement of the left-hand portion of the latch, such motion being limited by reason of the engagement of the horizontal top edge of said slot with the shoulder of the screw 57. By reason of the construction, the pushing pawl 50 is maintained in full or operative contact with the engaged tooth of the pinion 46 throughout the back spacing turning movement. Such movement of the pinion 46 will continue through a distance corresponding to one and one-half tooth spaces, at which time the pinion will be arrested and locked by the latch 49 due to the engagement of the pawl or device 51 with the said pinion. The pawl 51 is so related to the pawl 50 as to enter the third

tooth space in the pinion 46 above the one with which the pawl 50 is engaged, such entrance taking place near the end of the back spacing movement and so that the pinion 46 is blocked or positively arrested when it has been turned one and one-half spaces. The parts at this time will be related as illustrated in Fig. 4, from which it will be observed that the top edge of the slot 55 is in contact with its shoulder screw 57 and that the slot 56 is in substantial contact at its top and bottom with its screw 57. Consequently the latch or slide 49 is held from downward movement at this time, and the pawl 51, rigid with said latch and now engaged at its upper side with a tooth of the pinion 46 will positively prevent further turning movement of said pinion. As a result, the intermeshing rack 47 and the platen carriage, will of course, be also positively arrested. The construction is such that ample backward movement of the carriage is effected through the impulse received from the pinion 46 and the rack 47 to insure that the pawl 45 will pass over one of the teeth of the pinion 46 and will enter the tooth space immediately to the left of that with which it has been engaged prior to the back spacing operation. On the other hand, the interlocking of the latch 49 and the feed pinion 46 positively limits the turning movement of said pinion to the specified extent and prevents overthrow. The pawl 45 is held against bodily movement during the back spacing operation by reason of the fact that its pivot 45^a is fixed on the escapement wheel 43 which in turn is held from turning by the escapement dog 41.

When the back spacing key is released, the train of actuating devices positively connected with said key, comprising the lever 72, link 70 and bell crank 62, will be returned to normal position by the spring 75, thus restoring the latch 49 to the control of its own spring 59. From Fig. 4 it will be noted that in operated position the top of the inclined or cam portion of the under side of the slot 55 is in contact with the screw 57, so that the initial effect of the spring 59 will be not only to pull the latch rightward but also to raise or lift its left-hand portion including the pawl or lip 51. The slight lift thus imparted to the pawl 51 will permit the tooth of the pinion 46 engaged with its under side to move slightly upward, and of course will afford a corresponding slight turning movement of the pinion 46. This turning movement is sufficient to allow the pawl 50 to move freely under impulse of the spring 59 and not block the movement of the latch 49 by reason of engagement with the pinion 46 with which the pawl 51 would otherwise remain in interlocked engagement. In short, the construction is such that the

slight lift of the latch under the pull of its spring 59 is sufficient to free the pawls 51 and 50 from the pinion and permit the restoration of the latch to its normal position completely separated from the pinion. The turning of the pinion 46 as the latch 49 is retracted will be limited to a half-space movement by reason of the engagement of the escapement wheel with the dog 41, this half-space turning of the pinion being due to lost motion or interplay of its teeth with the pawl 45. In other words, the operative movement of the latch 49 communicates a full unit of back space turning movement to the pinion 46 and the platen carriage, together with a slight additional movement or excess, this excess of movement being taken up again when the latch 49 is retracted to normal position, the excess movement being useful in affording disengagement of the latch from the pinion 46. As a result of the described operation the carriage will be maintained in its back spaced position, one full letter-space to the right of where it was located prior to the back spacing operation. The back spacing operation above outlined may be repeated as often as or whenever desired.

From the foregoing it will be observed that the slide 49 and the pawls 50 and 51 are made of one piece and that the several parts all have a rigid relationship to one another.

In applying my improvements to a 92-character machine having a single shift, which machine is somewhat wider than the 84-character machine, it is not necessary to make any changes; the slide member or latch 49 being so proportioned that the contact face 54 will be in position to receive actuating impulses from the bell crank arm 63. This will be apparent from Fig. 5 which shows the parts applied to a 92-character machine wherein the pivot 65 of the bell crank 62 is located somewhat further to the right than in the prior described construction.

It will be observed that I provide by my present invention a simple yet highly effective back spacing mechanism which is adapted to more than one width of machine without any variation of parts.

Various changes may be made without departing from my invention.

What I claim as new and desire to secure by Letters Patent, is:

1. In back spacing mechanism for typewriting machines, the combination of a toothed wheel connected to the carriage, and a one-piece key operated slide, comprising a device co-operative with said wheel to back space the carriage, and a second device to arrest said wheel at the end of said back spacing movement, the said slide and the said first and second devices being all rigid.

2. In back spacing mechanism for typewriting machines, the combination of a toothed wheel connected to the carriage, and a one-piece key operated slide, having a rigid tooth for pushing against said wheel to turn it in back spacing direction, and having a second tooth also rigid with said slide to arrest said wheel at the end of the back spacing movement.

3. In back spacing mechanism for typewriting machines, the combination of a toothed wheel connected with the traveling carriage of the machine, a slidably mounted bar or plate provided with two angularly disposed integral lips adapted to fit in between the teeth of said wheel, one of said lips operating to push against the wheel to turn it for back spacing and the other of said lips operating to arrest the wheel at the end of the back spacing movement, said lips having an unvarying relationship.

4. In back spacing mechanism for typewriting machines, the combination of a toothed wheel connected with the traveling carriage of the machine, a member or latch operative to turn said wheel for back spacing, and key operated devices for contacting with and actuating said latch, said latch being provided with two contact faces, one for co-operation with said devices in a relatively wide typewriting machine, and the other in a narrower typewriting machine.

5. In back spacing mechanism for typewriting machines, the combination of a toothed wheel connected with the traveling carriage of the machine, a latch operative to turn said wheel for back spacing, and key operated devices comprising a swinging arm for pushing said latch, said latch being provided with two parallel contact faces, one engageable by said arm when the parts are employed in a wide machine, the same arm being adapted to contact with the other contact face in a narrower machine.

6. In back spacing mechanism for typewriting machines, the combination of a toothed wheel connected with the traveling carriage of the machine, a slotted bar, devices engaging in the slots in said bar for slidably supporting it, lips turned from the face of said bar to co-operate with said wheel, said bar being formed with a recess to provide two separate contact faces, and a key operated actuating device mountable to co-operate with either of said contact faces.

7. In back spacing mechanism for typewriting machines, the combination of a toothed wheel connected to the carriage, a key operated slide, a device on said slide co-operative with said wheel to back space the carriage, said device being normally separated from said wheel, said slide having limited rotary movement after said device engages with said wheel and during the completion of the sliding movement, and

means on said slide co-operative with said wheel to limit the movements of said slide.

8. In back spacing mechanism for type-writing machines, the combination of a toothed wheel connected to the carriage of the machine, a slidably mounted back spacing pawl for turning said wheel, key operated devices for actuating said slidably mounted pawl, and means rigid with said

pawl for co-operating with said wheel to limit the operative sliding movement of said pawl, said pawl and said means having an unvarying relationship.

Signed at the borough of Manhattan, city of New York, in the county of New York **15** and State of New York, this 1st day of May A. D. 1922.

EDWIN E. BARNEY.
